UNITED STATES PATENT OFFICE.

WILLIAM F. SEARGEANT, OF MARSHALL, MISSOURI.

WEATHER-BOARDING ATTACHMENT FOR TRY-SQUARES.

SPECIFICATION forming part of Letters Patent No. 349,905, dated September 28, 1886.

Application filed February 10, 1886. Serial No. 191,499. (No model.)

To all whom it may concern:

Be it known that I, WILLIAM F. SEARGEANT, of Marshall, in the county of Saline and State of Missouri, have invented a new and Improved Combined Try-Square and Scriber, of which the following is a full, clear, and exact description.

The object of my present invention is to provide a cheap, durable, and efficient weather-
10 boarding attachment for try-squares; and to this end the invention consists of a double-legged metallic scriber formed with a means for attachment to the stock of the square and carrying a scribing-point, as will be herein-
15 after more fully explained, and specifically pointed out in the claims.

Reference is to be had to the accompanying drawings, forming a part of this specification, in which similar letters of reference indicate
20 corresponding parts in all the figures.

Figure 1 is a side view of a try-square provided with my improved weather-boarding attachment. Fig. 2 is an inverted plan view of the attachment removed from the square. Fig. 3 is a plan view of a portion of the square and the attachment, and Fig. 4 is a similar view of a modified construction.

Referring now to the construction illustrated in the drawings, A represents an ordinary form
30 of try-square, and B the weather-boarding attachment or scriber, which is formed with two legs, C and D, the leg C being parallel with the leg D and projecting downward from a shoulder, a, which projects outward at right angles from near the upper end of the leg D. Just opposite the shoulder a there are formed two ears, b b, so spaced as to snugly admit the stock E of the square A, and in the projecting end of one of the ears b there is a threaded
40 socket arranged to receive a set-screw, F.

From near the lower end of the leg D there projects a lug, G, formed with an upwardly-extending pin, c, designed to enter a socket,

d, that is formed in the lower end of the stock E.

In applying the scriber to the stock of a try-square the pin c is inserted in the socket d, and the stock forced between the ears b b to the position shown in Fig. 1, where it is clamped to place by the set-screw F.

The shoulder a is formed with an aperture, e, and in this aperture there is placed a scribing-point, H, the idea being to have a marker always at hand. It will be understood that in using this attachment the leg C is placed over the board to be marked or scribed, the work being made by drawing the scribing-point H along the side edge of the leg D.

In Fig. 4 I show a modified construction wherein the attachment is fixed to the stock by a bolt, F', which passes through the stock, as shown.

Having thus described my invention, I claim as new and desire to secure by Letters Patent—

1. In a combined try-square and scriber, 65 the combination, with a try-square in the stock of which there is formed a recess, d, of a scriber formed with two legs, one of which is provided with ears b b and a lug, G, said lug having a pin, c, that fits within the recess d, a set-screw, F, being mounted in one of the ears b, substantially as described.

2. The combination, with a try-square, in the stock of which there is formed a recess, d, of a scriber formed with two parallel legs, 75 one of which legs is provided with ears b b, and a lug, G, having a pin, c, adapted to fit within the recess d, a set-screw or bolt being mounted in one of the ears b, the device being provided with a means for carrying a scribing-point, substantially as described.

WILLIAM F. SEARGEANT.
